UNITED STATES PATENT OFFICE.

GEORGE COLLIS, OF CLINTON, IOWA.

ICING-RACK.

1,130,376.

Specification of Letters Patent.

Patented Mar. 2, 1915.

Application filed June 9, 1913. Serial No. 772,644.

To all whom it may concern:

Be it known that I, GEORGE COLLIS, a citizen of the United States, residing at Clinton, in the county of Clinton and State 5 of Iowa, have invented certain new and useful Improvements in Icing-Racks, of which the following is a specification, reference being had therein to the accompanying drawing.

10 This invention relates to devices employed in connection with coating or icing articles of food and the like.

In connection with the icing of cookies and the like, it is usual to employ a so-called "rack" for holding the cookies while being iced: This rack comprises an appropriate supporting medium, usually in the form of a bar, provided with a series of pairs of pointed wires and with means for 20 supporting the rack. The cookies are pushed onto the points and, when the rack is full, the cookies and rack are dipped into a suitable mixture for coating them, as with an icing sugar, chocolate, or the like. They 25 are then hung on a suitable carrier which travels along for several hundred feet during which time the cookies dry.

In the construction of the rack, difficulty 30 has been experienced in economically mounting the pointed article-holding wires on the rack-bar. It is desirable that these be arranged in proper spaced relation; that they shall extend at approximately right angles from the bar and to each side there- 35 of; and that they be of diametral dimension considerably less than that of the supporting or rack-bar. It is also desirable that these pointed wires shall be welded to the supporting-bar, both from the stand- 40 point of economy and, also, for purposes of securing a structure of stability. It has been found that in welding these pointed wires to the bar, the heat necessary to soften the metal has necessarily to be so great that 45 it frequently results in the weakening of the wires. Moreover, a wire which is welded at right angles to a bar of larger diametral dimension is inherently weaker at its point of securement thereto. Hence, 50 methods of attaching these wires to the bar have been devised whereby this difficulty is overcome.

It has been with this object in view that I have devised the present invention: In one 55 aspect, it includes a metal bar of relatively large diametral dimension to which are

welded a series of article-holding wires of relatively smaller diametral dimension; and also reinforcing-plates adapted to securely hold the wires to the bar, and also to maintain them in proper spaced relation. These reinforcing-plates, acting in the nature of clamps, are sufficiently elongated to extend beyond the portions of the wires which have been heated by the welding operation and, 60 thus, the wires have restored to them what in effect is their original stiffness and strength. Moreover it is thereby afforded additional stability at its point of securement to the rack-bar. 65

With this object in view, the invention resides in the described article of manufacture, the details of which will appear hereinafter, and as illustrated in the accompanying drawing. 70

In the drawing: Figure 1 is a view in perspective of the rack; Fig. 2 is a fragmentary view, in section, and on an enlarged scale, illustrating a section of the bar with a pair of wires attached thereto; Fig. 3 is 80 a similar view showing one of the strengthening or reinforcing-plates attached to the structure; Fig. 4 is a similar view showing another of the pair of strengthening plates employed; and Fig. 5 is a view on an 85 enlarged scale of one of the strengthening plates.

Referring to the drawing, it will be seen that the numeral 1 indicates the supporting-bar or rod which, in this instance, is shown 90 as elongated and cylindrical. It may, however, be of any other appropriate form. Secured equidistantly on the bar 1 between its ends is a series of pointed pins or wires 2, 3. These are, preferably and as shown, 95 arranged in pairs and are secured to the bar 1 intermediate of their ends; wherefore, as will be seen, they extend therefrom in opposite directions. These wires occupy a position at right angles to the bar and are 100 mounted on opposite sides thereof, whereby they are spaced approximately the distance of the thickness of the bar. To effect a more rigid securement of these wires to the bar, reinforcing plates 5 and 6 are attached 105 in any suitable way to the bar and to the wires, as by soldering.

As already stated, one of the features of my invention resides in the manner of securing the plates rigidly to the bar and to 110 the wires: In this connection, I may explain that I prefer first to weld each pair of

wires (separately or together) to the bar. To do this, it is not necessary to subject the metals of the wire and bar to a very high degree of temperature, because reliance is not had solely upon the welding of the wires to the bar. Were a high degree of temperature employed, it would (because of the fact that the wires are of smaller diametral dimension than is the bar) tend to melt or soften the small wires at the point of contact and thereby make them weak. Hence, I resort to the use of strengthening media, preferably in the form of the aforementioned pair of plates which encompass the bar and also each wire of the pair. These plates are secured to the bar and also to the wires. From this it will be understood that the wires are themselves individually welded to the bar and the plates are attached thereto and also to the bars and, further, to each other: After the welding of the wires has been completed, as aforementioned, the whole structure is dipped in molten tin or the like which not only produces a smooth and clean surface but also effects the further function of soldering all of the joints together. As the particular use of this form of structure is such as to require that it shall be re-tinned after it has been completed, it is obvious that, unless the wires have been properly secured to the bar by electric welding, it would not be possible to dip them into the molten tinning metal without producing disintegration of the parts. In view of its advantages, I elect and prefer to produce the welding electrically.

I do not herein make claim to the rack, *per se*; but I do claim as of my invention a structure in which the wires are secured, as by welding, to the bar and, further, plates secured to the bar, to the wires, and to each

other, as by soldering, whereby a structure of proper strength is produced.

Having thus described my invention, what I claim as new and desire to secure by Letters-Patent is:

1. A device for coating or icing articles of food and the like, including an elongated supporting-instrumentality, a series of article-holding elements of relatively small dimension in cross-section arranged in closely juxtaposed pairs and mounted on said supporting-instrumentality, and reinforcing means for retaining said elements on the supporting-instrumentality. 55

2. An article-coating or icing device, including an elongated supporting-member; a series of pointed article-holding elements disposed in pairs and extending at right angles from opposite sides of said supporting-member, and formed of relatively small diametral dimensions; juxtaposed plates attached to said member and to said article-holding elements for holding the latter in spaced relation. 60

3. An article-coating or icing device, including an elongated supporting-member; a series of pointed article-holding elements disposed in pairs and extending at right angles from opposite sides of said supporting-member; and a pair of holding-plates encompassing said supporting-member and soldered thereto and to each other for securing the article-holding elements to said member in spaced relation with respect to each other and to said supporting-member. 70

In testimony whereof I affix my signature in presence of two witnesses.

GEORGE COLLIS.
